UNITED STATES PATENT OFFICE.

PAUL WALLACE, OF PHILADELPHIA, PENNSYLVANIA.

SPINNING-MACHINE.

1,131,580.

Specification of Letters Patent.

Patented Mar. 9, 1915.

Application filed September 18, 1912. Serial No. 721,031.

To all whom it may concern:

Be it known that I, PAUL WALLACE, a citizen of the United States, residing in Philadelphia, Pennsylvania, have invented certain Improvements in Spinning-Machines, of which the following is a specification.

My invention relates to textile machinery and consists of mechanism for winding yarn on to bobbins or other receptacles. My invention can also be used for spinning, twisting or doubling of yarns.

Heretofore in machines for winding and twisting yarn, bobbins having bores extending through their entire length were placed over spindles and the rotation of the spindle caused yarn to be wound thereon; the yarn passing through eyelets or rings in carriers and in each case requiring the bobbin or other receptacle to be lifted bodily from the spindle. In order to produce the necessary drag the bobbins were made to rest upon washers or other means which could not be controlled to suit different grades of yarn and are often varied during the winding of single sets of bobbins causing unevenness of wind and twist of the bobbin and yarn. Also, in machines such as the well known cap frame and flier frame it is necessary before removing a bobbin to lift the flier or cap and then to bodily lift the bobbin therefrom.

One object of my invention is to provide a machine of the above described type in which a proportionate and constant drag can be exerted for any quality and count of yarn to be wound.

Another object is to be able to change the degree of drag quickly and accurately to suit any quality or count of yarn.

40 A further object is to permit of easy insertion and removal of the bobbins.

A still further object is to so construct the mechanism that the yarn may be easily and quickly threaded into its proper winding position and that the machine may be manufactured and maintained at a low cost and easy of operation.

These and other advantages which will be brought out in the following specification I 50 attain in the following manner, reference being had to the accompanying drawings in which,

Figure 1, shows sufficient of a yarn wind-

ing machine to illustrate my invention; Fig. 2, is a transverse sectional view on the line 55 *a—a*, Fig. 1; Fig. 3, is a transverse sectional view on the line *b—b* Fig. 1; Fig. 4, is a sectional view taken on the line *c—c* Fig. 2 showing the winding wire and whirl flier in full lines; Fig. 5, is a sectional view taken 60 on the line *d—d* Fig. 1; Fig. 6, is a detail plan view of a winding wire which I employ; Fig. 7, is a fragmental view showing a form of drag-rod that I employ; Fig. 8, is a sectional plan view through the flier and 65 showing a modified form and arrangement of the winding wire; Fig. 9, is a modified form of drag producing means; and Fig. 10 is a fragmentary elevation of a portion of my invention shown on a reduced scale. 70

Referring to the drawings, 1 is the end frame having a rack 2 rigidly secured thereto, said rack forming the support for a plurality of bobbin winding mechanisms of which only one will be described in detail 75 hereinafter. A builder plate 3 is movable up and down by a series of rods 4 which may be operated by any well known mechanism. These rods 4 in the present instance pass through the spindle rail or rack 2; the 80 latter forming a guide therefor. A flanged sleeve 5 passes through the rack 2 and the flange rests on the upper face of the latter and forms a bearing for a whirl or pulley 6. A tube 7, forming a drag bearing as will be 85 described hereinafter, is rigidly secured to the stationary sleeve 5 and passes through the whirl 6 thereby forming a journal for the latter as is clearly shown in Fig. 1. Two arms 8, in the present instance diametrically 90 disposed extend upwardly from the whirl 6 and are connected at their upper ends by a bridge or plate 9; the latter having a depending journal pin 10 and an upwardly extending sleeve 11 rigidly secured thereto; 95 said latter sleeve being recessed or cutaway at 12 and 12^a for threading purposes as will be hereinafter more fully described. The top board 13, having a threading eyelet 14 passing therethrough, has a depending sleeve 100 15 which is adapted to telescope the upper end of the sleeve 11 and form a journal for the latter. A drag-rod 16, having a hooked arm 17 and head 18 rigidly secured at its upper end, passes through the tube 7 and 105 through a drag-varying bar 19; and a com-

pression spring 20, having one end secured to the rod 16 and the other end pressing against the lower face of the drag-varying bar, serves to hold the arm 17 in frictional contact with the upper end of the tube 7. A threaded bolt 21 is secured to the drag-varying bar 19 and loosely passes through a bracket 22 rigidly secured to the frame 1. A threaded-hand wheel or nut 23 is operable on the threaded portion of the bolt 21 so as to lower the bar 19 to compress the spring 20 and thereby increase the amount of friction between the arm 17 and the upper end of the tube 7.

15 In the present instance the yarn receptacle is in the form of a solid bobbin 24 having a recess 25 at its upper end and a recess 26 at its lower end; the recess 25 being adapted to receive the lower end of the pin 10 and the recess 26 being adapted to receive the head 18 of the drag rod 16, in a manner that the bobbin is free to move around the pin 10 and the head 18. The lower end of the bobbin is provided with a 25 pin 27 which projects into the path of the hooked end of the arm 17 so as to abut the same and prevent of a complete rotation of the bobbin around the drag-rod head 18. A compression spring 28 encircles the pin 10 and, by pressing against the bridge 9 and the top of the bobbin 24, tends to keep the latter in engagement with the head 18 during the winding operation. However, there is sufficient space between the lower end of 35 the pin 10 and the bottom of the recess 25 that the bobbin, if manually raised against the action of the spring, will be clear of the upper end of the head 18 and may be easily removed.

40 The builder plate 3 has an aperture 29 for each bobbin and of such a diameter as to allow the free rotation of the arms 8 on the whirl 6. An annular ledge 30 is formed around the aperture 29 and forms a seat for 45 a winding wire 31 as clearly shown in Figs. 1, 2, 3, 4, and 6; the free ends of the winding wire 31 being respectively coiled or turned around respective arms 8 so as to be free to move longitudinally thereon. A ring plate 32 is secured against the upper face of the builder plate 3 by screws 33 and acts to 50 confine the winding wire between the ledge 30 and the lower face of the ring plate 32. The flanged sleeve 5 is provided with oil recesses 34 so as to lubricate the tube 7.

55 The operation is as follows:—The empty bobbin is best inserted when the builder plate is in its uppermost position and by causing the lower end of the pin 10 to register with the recess 25. The bobbin is then raised so as to compress the spring 28 as shown in Fig. 5 until the bottom of the bobbin may be slid over the head 18 of the drag rod 16, the bobbin may then be released and 60 the expansion of the spring 28 will cause the

head 18 to project within the recess 26 and the bottom of the bobbin to rest on the arm 17 as is shown in Fig. 1. The hand wheel 23 may then be moved in order to place the required amount of downward pressure on 70 the drag or friction-producing rod 16 according to the quality of yarn to be spun. The whirl is then rotated by any well known mechanism, which is not shown in the drawing, and the arms 8 tend to rotate the winding wire; the yarn having been threaded through the eye 14, sleeves 15 and 11 and out of one of the cutaway portions 12 or 12^a, around one arm 8, through one of the curled portions of the winding wire 31, to the bobbin. It will thus be understood that the 80 yarn guide or wire 31 rotates at the same speed as the arms 8 and is, at the same time, raised and lowered by the builder plate to form the building of the bobbin. The drag 85 of the bobbin is produced by the pin 27 engaging the hooked end of the arm 17 for the reason, as before stated, that the arm 17 is in frictional engagement with the top end of the stationary tube 7.

90 It will thus be seen with this construction that the drag is under absolute control of the operator, that by simply turning the hand wheel 23, or other equivalent device, any degree of drag may be obtained to suit 95 the yarn being spun. Also, it is obvious that the winding of the yarn is positive, as the mechanism which forms the direct wind is movable directly with the whirl. Also, that there is a bearing for the winding 100 mechanism which is supported both by the rack 2 and by the top board 13 so that there is absolutely no unnecessary vibration of the machine, this produces a very even lap of the yarn on the bobbin. This latter advantage is equally true of the support of the 105 bobbin itself, as the bobbin is journaled at its base and top on journals which are rigidly secured.

110 In Fig. 9 is shown a modified form of mechanism for producing a drag on the rod 16. In this case the drag is caused by plates 35 and 36 acting against the atmosphere, these plates are made telescopic and slide one on the other to increase or decrease the 115 surface area. This construction may be used in cases where there is very slight changes in the degree of drag required such as when winding yarns of very delicate and soft texture.

120 In my invention the whirl 6, arms 8 and bridge 9 form a flier which is closed at both ends and which is supported at both ends; the winding wire being confined absolutely to the path of movement of the flier.

125 While I have shown the winding wire of a definite construction and having portions embracing the flier it will be understood that any means may be employed for looping the thread and holding it in a constant 130

- position relative to the rise and fall of the builder plate, for example, a winding wire 31^a may be slidably secured to an annular flange 30^a on the builder plate as shown in Fig. 8 and threaded from the yarn receptacle so that a portion of the flier, such as an arm 8, will contact with the yarn and thereby cause the wire 31^a to move at the same speed as the flier.
- 5 While I have only shown one hand wheel 23 and threaded bolt 21 for moving the drag-varying bar 19 it will be understood that any number of them can be used and the drag-varying bar 19 can be supported 10 and guided in any manner.
- 10 By having a pin 27 to form the turning means for the arm 17 and rod 16, a construction is provided which allows a certain amount of motion between the drag rod 16 and the bobbin and thereby compensates for 15 variations in the speed of the several parts in the machine. For example, if for any reason, such as a variation in the quality of 20 yarn being wound or a sudden change from a high to low speed of the machine, the bobbins should tend to hold back, they could 25 do so without being compelled to turn the friction rod 16 and possibly straining the 30 yarn.
- I claim:—
1. The combination of a rigidly mounted tube; a rod rotatable within the tube and having a portion frictionally bearing thereon; a bobbin mounted on the end of said 35 rod; means for winding yarn on the bobbin; and means for varying the friction between the said tube and the bobbin.
  2. The combination of a rigidly mounted tube; a rod rotatable within said tube and 40 having a portion in frictional engagement with the same; a bobbin secured to said rod; and means operable on said rod for varying the friction between the latter and said tube.
  3. The combination of a rotatable flier; a 45 bobbin; a rigidly mounted tube passing through said flier; a rod rotatable within said tube and detachably secured to said bobbin, said rod having a portion adapted to frictionally engage one end of said tube; with means operable on the rod for varying 50 the intensity of friction between the latter and said tube.
  4. The combination of a bobbin; a rigidly mounted tube; a rotatable rod passing through said tube and detachably secured to said bobbin, said rod having a portion adapted to frictionally engage one end of said tube; a spring operable upon the rod; a member operable on said spring; and adjusting means coöoperating with said member to vary the intensity of friction between said rod and tube.
  5. The combination of a supporting structure; a rotatable flier; a tube rigidly mounted 60 on said supporting structure and forming
  - a journal for said flier; a bobbin; a rod rotatably mounted in said tube and detachably connected to the bobbin, said rod having a portion adapted to frictionally engage said tube; and means operable on said rod for varying the intensity of friction between the latter and said tube.
  6. The combination of a plurality of bobbins; drag-producing members respectively connected to each bobbin; a bar; a spring connecting each of said members with the bar; and means for adjusting the bar to vary the intensity of drag on the bobbins.
  7. The combination of a rigid supporting structure; a rotatable flier journaled at both ends to the supporting structure; a friction producing member adjacent the flier; a friction rod having a portion normally resting on said latter member; a yarn receptacle resting on said friction rod; means on said yarn receptacle for engaging said friction rod to turn the latter; and means for varying the degree of frictional pressure between said rod and said latter member.
  8. The combination of a supporting structure including a stationary rack and a top board; a tube rigidly secured in said rack; a depending sleeve on said top board and in alinement with an eyelet in said top board; a flier having a projecting sleeve journaled on the said depending sleeve, said depending sleeve of the top board and projecting sleeve of the flier being cutaway at portions to permit the threading of the yarn through said eyelet; a builder plate; a yarn guide movable on said flier and by the builder plate; a yarn receptacle; a rod mounted within and bearing against the top of said tube; means on said yarn receptacle for engaging said rod; and means for varying the degree of frictional pressure between the said tube and the rod.
  9. The combination of a supporting structure including a stationary rack and a top board; a tube rigidly secured in said rack; a depending sleeve on said top board and in alinement with an eyelet in said top board; a flier having a projecting sleeve journaled on the said depending sleeve, said depending sleeve of the top board and projecting sleeve of the flier being cutaway at portions to permit the threading of the yarn through said eyelet; a builder plate; a yarn guide movable by said flier and by the builder plate; a yarn receptacle; a member on said flier engaging one end of said yarn receptacle; a spring interposed between said flier and the yarn receptacle; a rod mounted within and normally bearing against said tube, said yarn receptacle having a portion in engagement with said rod; and means operable on said rod to exert a variable degree of frictional pressure between said rod and said tube.
  10. The combination of a friction-produc-

ing member; a rod in frictional engagement with said member and having an arm rigidly secured thereto; a bobbin rotatably mounted on the end of the rod and having a projection positioned to move the arm and thereby turn the rod; and means for varying the friction between the rod and the member.

Copies of this patent may be obtained for five cents each, by addressing the "Commissioner of Patents, Washington, D. C."

In testimony whereof, I have signed my name to this specification, in the presence of two subscribing witnesses.
